UNITED STATES PATENT OFFICE.

JOHN GEORGE LEYNER, OF DENVER, COLORADO, ASSIGNOR TO THE J. GEO. LEYNER ENGINEERING WORKS COMPANY, OF LITTLETON, COLORADO, A CORPORATION OF COLORADO.

DRILL-SHARPENING MACHINE.

1,078,294.

Specification of Letters Patent. Patented Nov. 11, 1913.

Application filed April 1, 1912. Serial No. 687,847.

To all whom it may concern:

Be it known that I, JOHN GEORGE LEYNER, a citizen of the United States of America, residing in the city and county of Denver 5 and State of Colorado, have invented a new and useful Drill-Sharpening Machine, of which the following is a specification.

My invention relates to fluid actuated die-formed forgings making machines that are 10 adapted to be used in the forming, sharpening, and shanking of rock cutting drill bits, and that is also adapted to be used for making a great variety of small sized die formed forgings, and the objects of my invention 15 are: First, to provide a forging machine that is provided with a hammering, pressing and gripping vise, one jaw of which is a fixed stationary die jaw arranged on an anvil portion; the other jaw of said vise is 20 a reciprocally moving jaw that is adapted to be carried by a reciprocating hammer block that is arranged and adapted to reciprocate to and from the anvil and its stationary jaw and is arranged to strike hammer blows 25 which are actuated by fluid pressure against the stationary die jaw of the anvil, the jaws of said vise being interchangeable die jaws of such different shapes and forms as are necessary to form various articles such as 30 bolts having heads of different shapes, chisels, nuts, gads, handles of various kinds, spikes and various other articles, and especially the forming, shanking and sharpening of rock cutting drill bits on round, 35 hexagon, cruciform, octagon, or other forms of merchant bar tool steel used for rock cutting drill bits, such tool steel being either solid or provided with an axial aperture throughout its length, and known as hollow 40 tool steel. Second, to provide a die-formed forgings making machine that is adapted to be used as a drill bit forming, shanking and sharpening machine, and which is arranged to strike either light or heavy hammer blows and is arranged to give to drill 45 steel or metal bars, clamping, gripping, squeezing, swaging and holding pressures of any desired degree of power, which may be applied at the will of the operator, in the 50 forming, shaping and sizing of rock cutting drill bits, and for doing any other character of forging work within the capacity of the machine. I attain these objects by the mechanism illustrated in the accompanying drawings, in which:

Figure 1, is a side view of my improved die-formed forgings making machine, partly in section. Fig. 2, is a transverse, vertical sectional view of the same. Fig. 3, is a front view of the upper portion of the machine. 60 Fig. 4, is a plan view of the anvil portion of the machine, the support for the dolly operating cylinder being omitted. Fig. 5, is a side view of a completed drill bit; and Fig. 6, is a perspective view of a pair of 65 dies used in the production of the drill bits.

Similar letters of reference refer to similar parts throughout the several views.

Referring to the drawings, the numeral 1 designates a column that forms the foundation base portion of my die-formed forgings making machine, and hereinafter termed the base. This column form of base is provided with a floor flange portion 2, and with a top flange portion 3, on the upper surface of 75 which a slightly raised boss 4 is formed. The outside rim portion of this top flange 3 is provided with a circular row of holes 5, and the top of the base and rim is also cored out and an axial piston bore 6 is formed in 80 the column portion of the base, at the lower end of which an air inlet and exhaust aperture 7, is formed, that extends through the side of the base and is adapted to receive the end of an air supply pipe 9, that extends 85 from this inlet aperture to the air distributing throttle valve chest 10, of the machine, which will be described hereinafter. This top flange portion 3 of the base 1, supports 90 a cylinder 8, that is provided with a bottom edge flange portion 11 that is secured to the flange by any suitable means, preferably by means of cap screws 12, which are threaded into it from the under side of the flange. 95 This cylinder comprises a casting, preferably of circular form and containing an axial piston head bore 13, which is arranged to register in vertical axial alinement with the piston bore in the supporting base of the machine, but which is made much larger in diameter for a purpose which will be herein-after described. The top of this cylinder is provided with a vertically projecting block portion 14, which I term the anvil block, the central portion of the top surface of which is provided with a die vise, described and claimed in my copending application Serial No. 690,585. This die vise is composed of two independent half die jaws in which different shaped die recesses are formed, and 110

a different pair of die jaws are required for each different die forging made and some forgings require several different kinds of die jaws to complete them, and each set of jaws is secured in the anvil and die block and is used until as many of the articles as are required are operated on by this set of the dies, then this set of dies is taken out and another and different set is placed in the anvil and hammer block and another forging treatment is given to the article, and if this second forging treatment is not sufficient to finish the article, another and different set of die jaws may be used. I preferably illustrate and describe, however, a set of die jaws especially adapted to the sharpening of drill bits, and the anvil block is provided with a die jaw 15, which forms one jaw of the drill steel gripping vise. This die jaw has a head end portion 15^A and a body portion 15^B, and it is of half round or semi-circular form, and at the junction of the head and body portion, an inwardly beveled shoulder 16, is formed, which makes a dove-tailed form of recess between the shoulder and the body of the jaw. This jaw sets into a semi-circular shaped recess 17, which is made in two different diameters, 17^A and 17^B, which are formed in the top of the anvil with a similarly inwardly beveled or dove-tailed shoulder 18 between them, to which the dove-tailed shoulder of the jaw locks so that the jaw cannot be raised straight up out of the recess, and the inward bevel of the shoulder tends to draw the jaw down into and against the bottom of the recess. This jaw is arranged in the recess so that the end of its head portion will come even with the adjacent side of the anvil, and the jaw is secured in the recess by a bolt 19, which is placed in a groove 20, that is formed in the bottom of the recess 17, and at the inner end of this groove a recess 21 is formed, that is adapted to receive the head of the bolt 19. The threaded end of the bolt extends beyond the adjacent face of the anvil, and a washer 22, is mounted on it and overlaps onto the head end of the jaw, and a nut 23 is threaded onto the threaded end of the bolt and is turned to clamp the washer against the side of the anvil and forces the shoulder of the jaw into the dove-tailed shoulder of the recess in the anvil and rigidly and firmly locks the jaw to the anvil.

55 The other die jaw 24, of the drill steel gripping vise is made exactly like the jaw 15, and it is set into a similar shaped and shouldered recess 24^A, formed in the underside of a cross head hammer block 25, which is reciprocally mounted above the anvil and is arranged to strike vertically reciprocating hammer blows against its jaw and against such other jaws and former dies as may be secured to the anvil.

65 The upper jaw 26, of the drill steel grip-

ping vise is secured to its recess with its face even with the adjacent side of the hammer block by a bolt 26, which is inserted in a groove 27, at the inner end of which a recess 28 is formed for the head 29 of the bolt to fit into. The outer end of the bolt is threaded and is provided with a washer 30, and with a nut 31 that clamps the upper jaw against and into the recessed shoulder of the cross head. Inasmuch, however, as these jaws have to be removed and replaced by others of different die forms, and as this upper jaw holding bolt would fall out of its groove in the cross head every time the upper jaw was removed, if not secured in the groove, it is necessary that some means be employed to hold it securely in its groove when its nut 31 is loosened and the jaw is removed. And while there are a number of ways in which this bolt may be secured in its groove, I preferably secure it in such a manner that it will remain securely in the groove and at the same time may be readily removed and be replaced by a new bolt when necessary. In the hammer block, in alignment with the groove in which the bolt fits, a hole 32 is drilled from the inner wall of the recess in which the head of the bolt fits, and in this hole I place an expansive coiled spring 33, which is arranged and adapted to bear against the end of the head of the bolt with sufficient pressure to clamp the inside head of the bolt tightly against the opposite side of its recess and hold it in its groove.

100 The die jaws 15 and 24 have flat meeting faces which are provided with two different shaped die recesses 35 and 36. The recess 35 is a straight circumferentially curved recess that extends along the greater portion of the length of each of the jaws and is of a size when both jaws are closed together, to grip the bar of drill steel on which rock cutting lips are to be formed, and the recess 36 is a circumferentially curved tapering recess that flares divergingly outward from the inner end of the straight die recess of the jaw to the end of its head end portion, and is adapted to form a diverging tapering neck portion on the bar of the drill steel that extends 110 from the body of the bar of steel to the outside peripheral diameter of its rock cutting lips end of the bar of drill steel, and the end of the bar of steel which is heated is upset by the reciprocal movements of the dolly to 120 completely fill this tapering diverging recess of the jaw dies and form the rock cutting lips on its face end, as will be fully described hereinafter. This pair of circumferential curved form of recessed jaw dies is 125 especially adapted to grip and hold round bar drill steel, but die jaws are made with cruciform, hexagon, octagon, or other forms of die recesses. These die jaws preferably extend across the width of the top of the 130

anvil and hammer block, but that end portion of the die jaws that grips and holds the body of the bar of drill steel of the drill bits can be extended rearwardly beyond the anvil portion, and when die jaws are used that are longer than the width of the anvil, a shelf portion 38 is formed below the top of the anvil portion, and a similar shelf portion 39, is formed above the lower end of the hammer block and opposite to the shelf 38, of the anvil, upon which supporting blocks, not shown, may be placed to support the overhanging rear ends of the die jaws. These shelf portions 38 and 39, are made long enough on the sides of the anvil and cross-head to receive two pairs of former die jaw blocks 43 and 44, which are made to fit on the shelves, and to be clamped thereon by the clamping plates 41, which are bolted to the adjacent sides of the anvil and the hammer blocks, by bolts 42, and are arranged so that their top edges lap over onto the adjacent ends of these die jaw former blocks, and clamp them against the sides of the anvil and hammer block. These two pairs of former die blocks are independent of each other, as shown, and they are placed on the shelves on opposite sides of the center of the anvil, thus leaving a clear unobstructed space between the shelves and between the former blocks to the drill steel gripping and dolly entering dies.

The former blocks 43 are provided with die slots 47, which are adapted to receive the ribs of cruciform shaped drill steel, and the former blocks 44 are provided with a wedge-shaped projecting rib 48, for pressing out the corners between the ribs of cruciform steel, and also for pressing the grooves 45 between the rock cutting lips 45^A of four and six point drill bits, and which I term the clearance former block, but blocks may be used having slots or recesses or projections of different forms for special kinds of die forging work.

When making rock cutting drill bits that are provided with five, six, or more rock cutting lips or points on either round, hexagon, cruciform, or other shape of drill steel, I employ one of the V-shaped blocks 44 on the shelf of the hammer block, and on the shelf of the anvil directly below it I place a block 46 provided with a semi-circular recess 47'. Both of these blocks are arranged with their die surfaces inclining or tapering toward their bottom sides and toward the shelves on which they rest, and consequently their opposing die surfaces form a divergently flaring space between them in which the head end of the drill bit is placed, and the curved tapering portion of the head end of the drill bit rests in the semi-circular curved recess of the lower block, and the V-shaped die block is used to form the grooves 45, between the

rock cutting lips of the head by pressing or striking the V-shaped dies down into the heated head end of the drill bits by the reciprocal movement of the hammer block.

The ends of the anvil and hammer block that are on the same side of the machine as its throttle valve, are provided with a pair of projecting lugs 49 and 49^A, that are provided with oppositely arranged faces that are cut far enough below the main opposing surfaces of the anvil and hammer block to receive flat plate jaws 50 and 50^A, which are placed on and are secured to them by any suitable means, but preferably by screws 50^B. These flat jaws are positioned to bring their top surfaces even with the top surface of the anvil and with the anvil engaging surface of the hammer block. These flat plate jaws form a vise that is used to grip and hold drill steel metal bars and die forgings of various kinds and drill bits between their different step forging treatments, when it is necessary to grip and hold them for any purpose, such, for instance, as for holding heated hollow drill steel, while a cold steel pin is driven into them to preserve the round form and size of the aperture, while the shank ends are being formed on them.

The opposite ends of the anvil and hammer block from the ends that carry the flat jaws, are also provided with projecting lugs 51 and 51^A, which are formed with oppositely arranged faces that are cut far enough below the level of the opposing surfaces of the anvil and hammer block to receive a pair of shearing jaws 52 and 52^A, which are arranged to cut or trim or shear either cold or heated metal rods, bars, plates, or drill steel, either partially or wholly in two. These shearing jaws may be secured to the opposing faces of these projecting lugs by any suitable means, but are preferably secured thereto by screws 52^B, and their shearing edges are arranged to slightly overlap in proper shearing relation.

The cylinder bores 6 in the column 1, and 13 in the cylinder 8, are of differential areas, and in them a piston head is reciprocally mounted, the opposite pressure engaging surfaces of which are also of differential areas. The upper end 53 of this piston head, is made in the form of a disk and is fitted reciprocally in the piston bore 13 of the cylinder. This disk-shaped end 53 of the piston head is provided with a piston head extension portion 54, which is considerably smaller in diameter than the disk portion, and extends axially from the large disk-shaped piston head down into and fits reciprocally in the piston bore of the base of the machine.

The piston head 53 and its extension 54, are provided with annular grooves, in which are placed packing rings 55^A, which pre-

vent leakage of air past their respective end portions. The hammer block 25, is connected to the disk portion of the piston head by two large bolts 56 and 57, which extend 5 down through the hammer block and the anvil block to and through the disk, and their head portions 58 rest on top of the hammer block, while their lower ends extend slidably through apertures 59 and 60, formed in 10 the anvil block into the cylinder, and they extend through the disk portion of the piston head, and their lower ends are threaded and are provided with nuts 61, which preferably are of thimble form, which screw up 15 against the bottom of the disk portion of the piston head. Set screws 61^A are threaded through the nuts against the bolts and act to lock the nuts to the bolts against accidental displacement. Apertures 62 are formed 20 through the top flange of the base directly underneath and in alinement with these bolts and nuts, that enable these nuts to be turned on or off the ends of the bolts. These bolts are positioned on opposite sides of and 25 at equal distances from the longitudinal axial center of the vise jaws of the anvil and hammer block, and they are each provided with packing rings 62^A, which are arranged in that part of their length that lies 30 in the slideway apertures in the anvil block portion of the cylinder. These packing rings prevent leakage of the compressed air or other actuating fluid through the bolt apertures from the upper portion of the cylinder 35 der around these bolts.

It is essential that the bolts be rigidly secured to the hammer block in order that they move and act together as an integral monolithic member, and while there are many 40 ways in which these bolts may be rigidly secured to the hammer block, I preferably make them of steel and harden and grind and press them into and through the hammer block by hydraulic pressure, which 45 method insures that they will have an equal and central bearing on all the area of the apertures into which they are pressed, and insures true axial alinement with each other and at right angles to the anvil engaging 50 surface of the hammer block.

The die forging machine is provided with a throttle valve, to which the actuating fluid, which is preferably compressed air, flows from a source of supply through a hose or 55 a pipe 64. This throttle valve may be of any suitable type to reciprocate the piston in the cylinder in such a manner as to effect light or heavy or single or successive reciprocal hammer blow striking, or for effecting 60 pressing, squeezing or swaging pressure movements of the hammer block and its die jaw against the die jaw of the anvil. This valve is provided with an operating handle 65 and the valve chest is preferably provided with stop lugs 66 and 67, and with a

stop or indicating finger 68 to define the operative movement of the valve-disk 63. The actuating fluid is conveyed from the valve chest 10, through the pipe 9 to the lower end of the cylinder, below the lower end of the stem portion of the piston, and a port 69 extends to the top of the cylinder and enters it above the large disk-shaped head of the piston. I have not illustrated the detail construction of the interior mechanism of this throttle valve, as my invention contemplates the use of any operative multiple port throttle valve that can be adapted to operatively reciprocate the hammer block operating piston. A throttle valve, however, especially designed for use with this forging machine, is illustrated in my pending application for a patent for a drill sharpener, Serial No. 686,133, filed March 25th, 1912.

My present invention can be combined with any kind of a coöperating cylinder and piston that is arranged to reciprocally drive and upset the ends of drill steel with dollies and formers and other character of dies that are adapted to work against the ends of steel or iron bars or pieces of any forging metal. This dolly or former die driving cylinder may be supported in any suitable manner on one side of the base or of the anvil or of the cylinder, in operative relation to the center of the die jaw that is secured in the anvil.

My present invention contemplates the use in coöperating relation with my steel or iron bar gripping, pressing and hammering 100 die jaws of any cylinder and piston mechanism arranged to drive die formers or dollies against the ends of steel or iron bars, rods or chunks of any suitable forging metal held in the die jaws. I have, however, illustrated in side elevation in Fig. 1 an operative dolly driving engine 70, which is also connected to the throttle valve chest 10 by a hose 71. In this engine 70, a forging upsetting dolly 72 is mounted in operative 110 forging upsetting relation to the die jaws of the anvil and hammer block, and while it is necessary to have an upsetting dolly driving engine for some kinds of die-formed forgings making work, especially for making 115 the rock cutting lips or points and also when forming locking lugs on collars and other forms of shank ends of rock cutting drill bits, the dolly driving engine as illustrated is not however an essential part of my present invention, but forms a feature of it that operatively coöperates with it when producing certain kinds of forgings. My invention, however, contemplates the use of any operative dolly driving engine that can be 120 used with my die-formed forgings making machine. As more particularly described and claimed in the aforesaid copending application Serial No. 686,133, this engine 70 is slidably mounted on a slideway 73, which 125

as illustrated is formed on the end of an arm 73^a, that projects from the cylinder 8 of the die-formed forgings making machine, and it is provided with a feed screw 74 to which a handle 75 is secured, by which the cylinder may be moved back and forth on its slideway far enough away from the vise jaws to permit a dolly to be inserted in the guide flange, or to be removed from it when desired. The engine is also provided with clamping bolts 75^a, by which it may be clamped in adjusted positions rigidly to its slideway. The dolly 72 is reciprocally impinged against the ends of drill bits or other articles held in the vise jaws, and is driven on its forward stroke by a hammer piston that is reciprocally mounted in the cylinder of the engine by the actuating fluid flowing through the hose 71 from the throttle valve, as is well understood and in a manner that is common to several of the dolly driving engines of drill bit forming and sharpening machines in public use. The dolly is moved on the rearward stroke of its reciprocal movements by a spring 76, which is arranged to effect its rearward stroke.

A more complete description of a dolly driving engine, as well as a more complete description of the dolly, can be found in my above mentioned pending application.

The operation of my improved die forging machine is as follows: The throttle valve is manipulated by the operator to admit the actuating fluid first to one end of the cylinder and its piston and then to the other end in any desired volume and in alternating order, so as to alternately reciprocate the piston in the cylinder and thus raise the hammer block or to force it down either slowly and with lightly engaging, pressing, squeezing, or swaging strokes with the die jaw of the anvil, and when desired to hold the hammer block die jaw down against drill steel or any other article that may lie in the die jaw of the anvil, with great pressure for as long a time as is necessary to properly give a forging treatment to the same, or to drive it down with one or more rapid successive hammer striking blows of great force, the machine being capable of effecting blows of any desired force or pressures, owing to its piston being provided with ends of different areas, the smaller end of which is adapted to simply raise the weight of itself and of the hammer block and its connections, while the upper end of the piston is given an area that permits it to be driven down against the anvil's die jaw with hammer blows that are powerful enough to forge any size of steel or iron bars or blocks or slugs of any forging metal used for medium sized forge work such as the forming, shanking and sharpening of drill steel and the making of iron or steel bolts with heads of various kinds, nuts, spikes, gads, chisels

and other types of forgings, it only being necessary to provide die jaws of the form of each article that is to be made.

My invention provides a small sized but powerful die formed forgings making machine suitable for the use of mines, quarries, railway, irrigation, and mine tunnel rock work, and especially for use in machinery manufacturing plants that require a quick acting efficient machine for making small die-formed forgings of various kinds, and of different characters, and while I have illustrated and described the preferred construction and arrangement of my improved die-formed forgings making machine, I do not wish to be limited to the construction and arrangement shown, as changes may be made in its various parts without departing from the spirit of my invention.

Having described my invention, what I claim as new and desire to secure by Letters Patent, is:

1. In a drill-forming machine, a supporting base, a cylinder mounted on said base, an actuating fluid controlling valve on said cylinder, said cylinder and base being also provided with two cylindrical bores of different diameters, the larger of which is in said cylinder, a piston head of two diameters fitting reciprocally the two bores of said cylinder, the larger portion of which is in the bore of said cylinder, said base being provided with suitable actuating fluid inlet and exhaust ports to the opposite ends of said piston head from said throttle valve, an anvil portion mounted on said cylinder, and a hammer block connected to the piston head of said cylinder and arranged above said anvil to strike reciprocal blows against said anvil, said different diameters of the piston head and cylinder and said actuating fluid ports being so relatively arranged that said hammer block is raised by the upward movement of the smaller diameter of said piston head and is lowered by the downward stroke of the larger diameter of said piston head, whereby said hammer block is caused to strike hammer striking blows against said anvil.

2. In a drill-forming machine, a supporting base, a cylinder mounted on said base, said base and cylinder being provided with piston bores of two different diameters, a piston head having opposite end portions of different areas and fitting reciprocally in the bores of said base and cylinder, means including a controlling valve for reciprocating said piston head, an anvil portion on top of said cylinder, vertically arranged slideways in said anvil portion, guide rods secured at one end to said piston head and extending slidably through said slideways, a hammer block secured vertically above and over said piston head to said guide rods and arranged to strike vertical reciprocating blows against

- said anvil, the opposing faces of said anvil and hammer block being provided with die jaws arranged to register opposite to each other upon the downward movement of said hammer block.
5. 3. In a drill-forming machine, the combination of a supporting base provided with a cylindrical piston bore, a cylinder mounted on said base provided with a cylinder bore that is arranged concentric to the bore in said base and is of much larger area, a piston head comprising a disk portion fitting the larger bore in said cylinder, and a stem portion fitting the bore in said base, said base and cylinder being provided with suitable air inlet and exhaust ports, an anvil portion on said cylinder, a pair of bolts connected to opposite sides of the disk portion of said piston head and extending slidably upward through said anvil, a hammer block secured to the upper ends of said bolts above said anvil and arranged to be vertically reciprocated to and from said anvil in operative hammer blow striking forging relation thereto, and a throttle valve connected to the inlet and exhaust ports of said base and cylinder, and arranged to operatively admit compressed air to them.
4. In a drill-forming machine, the combination of the base, the cylinder mounted on said base, said base being provided with a small piston bore, and said cylinder being provided with a piston bore of much larger diameter than the piston bore of said base, a piston head of two different diameters fitting reciprocally in the piston bores of said cylinder and base, said base and cylinder being provided with actuating fluid inlet and exhaust ports connecting operatively to said piston bores to reciprocate said piston head, an actuating fluid receiving and controlling throttle valve arranged on said cylinder and operatively connected to said cylinder inlet and exhaust ports to control the reciprocal movements thereof, a forging anvil portion on top of said cylinder, guideway apertures through said anvil portion and the top of said cylinder into its piston bore, bolts secured in said piston head and extending slidably through said guideways, a packing medium connected to said bolts for preventing leakage of actuating fluid past said bolts through said guideways from said piston bore, and a hammer block secured to the ends of said bolts that project from said cylinder and anvil and arranged and adapted to be impinged against said anvil in unison with and by the reciprocal strokes of said piston head in said cylinder and base.
5. In a drill-forming machine, a lower member having an inner chamber of two diameters, a stationary anvil - member mounted on said lower member, a hammer-block mounted over said anvil-member, a piston comprising a cylindrical lower portion fitting within the chamber along its portion of smaller diameter and a disk-shaped head within the portion of said chamber of greater diameter, connections between said hammer-block and said piston, and means for controlling the supply of fluid under pressure to the opposite ends of said piston.
6. In a drill-forming machine, a lower member having an inner chamber of two diameters, a stationary anvil - member mounted on said lower member, a hammer-block mounted over said anvil-member, a piston comprising a cylindrical lower portion fitting within the chamber along its portion of smaller diameter and a disk-shaped head within the portion of said chamber of greater diameter, bolts secured at one end to said hammer-block and at the other end to said piston, and means for controlling the supply of fluid under pressure to the opposite ends of said piston.
7. In a drill-forming machine, a lower member having an inner chamber of two diameters, a stationary anvil - member mounted on said lower member, a hammer-block mounted over said anvil-member, a piston comprising a cylindrical lower portion fitting within the chamber along its portion of smaller diameter and a disk-shaped head within the portion of said chamber of greater diameter, vertical bolts secured at their upper ends to said hammer-block and at their lower ends to the disk-shaped head of said piston, and means for controlling the supply of fluid under pressure to the opposite ends of said piston.
8. In a drill-forming machine, a lower member having an inner chamber of two diameters, a stationary anvil - member mounted on said lower member, a hammer-block mounted over said anvil-member, a piston comprising a cylindrical lower portion fitting within the chamber along its portion of smaller diameter and a disk-shaped head within the portion of said chamber of greater diameter, vertical passage-ways in said lower anvil-member, vertical bolts secured at their upper ends to said hammer-block and at their lower ends to the disk-shaped head of said piston, and adapted to move in said passage-ways, and means for controlling the supply of fluid under pressure to the opposite ends of said piston.
9. In a drill-forming machine, a lower member having an inner chamber of two diameters, a stationary anvil - member mounted on said lower member, a hammer-block mounted over said anvil-member, a piston comprising a cylindrical lower portion fitting within the chamber along its portion of smaller diameter and a disk-shaped head within the portion of said

chamber of greater diameter, vertical bolts passing through and secured at their upper ends to said hammer-block and passing through and secured at their lower ends to
5 the disk-shaped head of said piston, and means for controlling the supply of fluid under pressure to the opposite ends of said piston.

In testimony whereof I affix my signature in presence of two witnesses.

JOHN GEORGE LEYNER.
